UNITED STATES PATENT OFFICE.

ERNST MESEKE, OF CHICAGO, ILLINOIS.

LOCOMOTIVE JOURNAL-BOX.

SPECIFICATION forming part of Letters Patent No. 414,982, dated November 12, 1889.

Application filed April 4, 1889. Serial No. 305,945. (No model.)

To all whom it may concern:

Be it known that I, ERNST MESEKE, a citizen of the United States, residing at Chicago, in the county of Cook and State of Illinois, have invented certain new and useful Improvements in Locomotive Journal-Boxes, of which the following is a full, clear, and exact description, that will enable others to make and use the same, reference being had to the accompanying drawings, forming a part of this specification.

This invention is an improvement on the device set forth in Letters Patent No. 394,988, issued to me and dated December 25, 1888.

The object is to adapt the slides shown in the above patent for closing up the space on the under side of the axle as the brass wears, to be used in combination with the ordinary oil-cellars, as will be hereinafter set forth.

Figure 1 is an end elevation; Fig. 2, a transverse section; and Fig. 3 a longitudinal horizontal section in the angular plane 3, Fig. 1.

Referring to the drawings, A represents the ordinary oil cellar or box commonly used, the relative position of the truck-axle being indicated by dotted lines. The vertically-adjustable slides B B' are located inside of and at each end of the cellar, and are curved out to correspond to the ends C C' of the cellar and the circle of the axle. These slides are provided with elongated apertures a a' a', as shown in Figs. 2 and 3. The end C of the cellar comes next to the wheel, and has the head b of the bolts D D countersunk, so as to be entirely out of the way, and prevent the same from turning when the clamping-nuts b', placed on the inner threaded ends of the bolts, are turned. The washers b² are interposed between the nuts b' and the inside surface of the slide B. A lining b³, of leather, rubber, or other suitable material, is inserted between the slides and the inside ends of the cellar. The slide B is provided with the inwardly-projecting lug b⁴, (see Figs. 2 and 3,) which provides for the raising of said slide by reaching in from the opposite end of the cellar, as the close proximity of the hub of the truck-wheel prevents

access from the outer end. The bolts D' D' in the inner end of the cellar for adjusting the slide B' are inserted from the inside, the screw-threaded adjusting-nuts d d being placed outside on the screw-threaded ends. 55 The slide B' is provided with the outwardly-projecting lug d', for convenience in adjusting the same. The notch d² in the end of the cellar receives the lug d' and permits the slide to drop down flush with the inclosing 60 end. The slide B may be provided with a recess in place of the inwardly-projecting lug, which will receive the end of a rod or any suitable tool used in raising the slide. The flexible lining prevents the jar incident 65 to the travel of the locomotive from working the bolts loose, so that the slides drop down. The slides may be set up from time to time, as the wearing of the brass may require, thus 70 keeping the space between the axle and cellar closed, the dust and dirt entirely excluded, and also preventing the packing or oil absorbent from working out.

Having thus described my invention, what I claim as new, and desire to secure by Letters Patent, is—

1. In a locomotive journal-box, the combination, with the oil-cellars, of the vertically-adjustable slides located at and inside of the respective ends of said cellar, means, substantially as described, for retaining said slides in the position to which they are adjusted, and the flexible lining-pieces interposed between said slides and the ends of the cellar, substantially as and for the purpose set forth.

2. In a locomotive journal-box, the combination, with the inner end of the oil-cellars, of the vertically-adjustable slide B', provided with elongated apertures a' a', and the outwardly-projecting lug d, the flexible lining interposed between the cellar end and slide B', the adjusting-bolts passing through from the inside, and the clamping-nuts engaging with said bolts, substantially as and for the purpose set forth.

ERNST MESEKE.
